J. MANELICH.
FENCE PANEL.
APPLICATION FILED NOV. 25, 1919.

1,342,453.

Patented June 8, 1920.

INVENTOR.

John Manelich
BY George C. Heinrich

ATTORNEY.

UNITED STATES PATENT OFFICE.

JOHN MANELICH, OF YOUNGSVILLE, PENNSYLVANIA.

FENCE-PANEL.

1,342,453.

Specification of Letters Patent.

Patented June 8, 1920.

Application filed November 25, 1919. Serial No. 340,534.

To all whom it may concern:

Be it known that I, JOHN MANELICH, a citizen of Canada, residing at Youngsville, county of Warren, and State of Pennsylvania, have invented certain new and useful Improvements in Fence-Panels, of which the following is a specification.

This invention relates to fences and more particularly to metal fences made up of a series of spaced members bound together.

The invention has for an object to provide a simple construction in which the panels or sections between the posts are made up in individual units which may be readily assembled together or taken apart.

For further comprehension of the invention, and of the objects and advantages thereof, reference will be had to the following description and accompanying drawings, and to the appended claims in which the various novel features of the invention are more particularly set forth.

Figure 1 of the drawings is an elevation of one section or panel of a fence constructed according to my invention.

Fig. 2 is a detail enlarged horizontal section on the line 2—2 of Fig. 1.

Fig. 3 is a detail enlarged vertical section on the line 3—3 of Fig. 1.

In the drawings 1 and 2 represent a pair of metal fence parts which may be of suitable construction and set in the ground in the usual manner. Extending between these posts are the top and bottom fence rails 3 and 4 which may be made of angle iron and rigidly secured to the posts in any suitable manner.

Extending between and rotatably mounted in the rails 3 and 4 adjacent the respective posts 1 and 2 are a pair of vertical bars 5 and 6 of circular cross section having squared upper ends 7 and 8 which project upwardly beyond the top rail 3, these bars serving as a support for the fabric constituting the panel.

This fabric consists of a plurality of horizontal rods 9 which extend between the bars 5 and 6 and are suitably spaced apart, the ends of these rods being hooked to take over the bars as indicated at 9' in Fig. 3.

Formed on each of the bars 5 and 6 extending substantially the entire distance between the top and bottom rails is a rib 10 which may as here shown be in the form of a separate strip inserted in a suitable

slot in the rails, this rib being provided to enable the hooked ends 9 to be sprung off the bars when desired by simply rotating the latter.

Extending vertically between the rods 9 to complete the panel are short rod lengths 11 which are bent at one end, as shown at 12 in Fig. 2 to form eyes by which they are hinged upon the rods. Each of these rods 9, except either the top or bottom one, has a series of the rod lengths 11 hinged thereon by means of the eyes 12, the opposite ends of the rod lengths being provided with the integral clip-jaws 13 which grip the adjacent ones of the horizontal rods 9 as shown in Fig. 2 these jaws being normally bowed toward one another and pressed upon the rods 9.

The rod lengths 11 are preferably arranged in vertical rows spaced evenly between the bars 5 and 6 to present the appearance of stakes or pickets, the jaws of one rod length, gripping the rod 9 closely adjacent the eye of the next rod length of the vertical series or row.

Having thus described my invention what I claim as new and desire to secure by Letters Patent, is—

1. In a fence panel consisting of posts, top and bottom rails extending between said posts, bars extending between and rotatably mounted in the said rails adjacent said posts, a panel forming structure connected to said bars, and means whereby said structure may be displaced from said bars by rotation of the latter.

2. In a fence panel consisting of posts, top and bottom rails extending between said posts, bars extending between the said rails adjacent the said posts, a series of horizontal rods hooked upon said bars at their ends, and a series of vertical rod lengths hinged upon the said horizontal rods at one end, and means detachably connecting the opposite ends of said rod lengths to the adjacent ones of the said horizontal rods.

3. In a fence panel consisting of posts, top and bottom rails extending between said posts, bars extending between the said rails adjacent the said posts, a series of horizontal rods hooked upon said bars at their ends, and a series of vertical rod lengths hinged upon the said horizontal rods at one end, and means detachably connecting the opposite ends of said rod lengths to the adjacent ones of the said horizontal rods.

ones of the said horizontal rods, said means comprising a pair of integral clip-jaws formed on the ends of the said rod lengths.

4. In a fence panel consisting of posts, 5 top and bottom rails extending between said posts, bars extending between the said rails adjacent the said posts and rotatably mounted therein, a series of horizontal rods having their ends hooked over said bars, 10 projections carried by the said bars, adapted

to disengage the said hooked ends from the bars when the latter are rotated, a series of rod lengths hinged at one end to said horizontal rods, said rod lengths having integral clip-jaws on their opposite ends engaging adjacent ones of the said horizontal rods. 15

In testimony whereof I have affixed my signature.

JOHN MANELICH.
